PRINTING PRESS

Lucius Emery Aborn, River Forest, Ill.

Application November 15, 1933, Serial No. 698,212

8 Claims. (Cl. 101—232)

The present invention relates to new and useful improvements in printing presses and has for its primary object to provide, in a manner as hereinafter set forth, a printing press embodying a novel construction, combination and arrangement of parts through the medium of which either sheets or a web may be fed to said press.

Other objects of the invention are to provide a press of the aforementioned character which will be comparatively simple in construction, strong, durable, highly efficient and reliable in operation, compact and which may be manufactured at low cost.

15 All of the foregoing and still further objects and advantages of the invention will become apparent from a study of the following specification, taken in connection with the accompanying drawings wherein like characters of reference 20 designate corresponding parts throughout the several views, and wherein:—

Figure 1 is a view principally in side elevation of the invention.

Figure 2 is a detail view in vertical section, 25 showing the means for adjustably mounting the impression roller on the supporting structure or frame of the press.

Figure 3 is a detail view in horizontal section, taken substantially on the line 3—3 of Figure 2.

30 Figure 4 is a view in side elevation of the feeder.

Figure 5 is a detail view in section, taken substantially on the line 5—5 of Figure 1.

Figure 6 is a fragmentary view in top plan of the feeder board.

35 Figure 7 is a fragmentary view in vertical longitudinal section through the feeder and board.

Figure 8 is a sectional view through the feeder, taken substantially on the line 8—8 of Figure 4.

Figure 9 is a detail view in section through the 40 feeder drive mechanism, taken substantially on the line 9—9 of Figure 4.

Figure 10 is a detail view in side elevation of the cam which operates the feeder.

Figure 11 is a detail view in plan of the cam.

45 Figure 12 is a detail view in plan of one of the vertically slidable rack bars.

Figure 13 is a detail view in perspective of one of the feeder shaft bearings.

Referring now to the drawings in detail, it will 50 be seen that the embodiment of the invention which has been illustrated comprises a supporting structure or frame which is designated generally by the reference numeral 1 and in which the cylinder 2 is operatively mounted in the usual manner. The supporting structure or frame 1

of the press includes uprights 3 having mounted on their inner sides pairs of spaced, vertical strips 4 defining channels 5. The strips 4 thus constitute guides for the vertically adjustable rack bars 6 which are fixed on the ends of upper and lower rods 7 and 8, respectively, said rack bars 6 having tongues 9 in the form of strips thereon which are engaged in the channels 5.

Extending transversely between the uprights 3 is a shaft 10 having gears 11 fixed thereon which are engaged with the rack bars 6. Hand wheels 12 are fixed on the ends of the shaft 10. Mounted for swinging movement in a vertical plane on the upper rod 7 are arms 13 between which the impression roller 14 is journaled.

The reference numeral 15 designates an elevating rod for the impression roller 14 which is adjustably and detachably connected to one of the arms 13, as at 16. The lower end of the elevating or lifting rod 15 is connected to a bracket 17 by a toggle 18. The reference numeral 19 designates a foot plate on the supporting structure 1 of the press from which a hanger 20 depends. Mounted for rocking movement on the hanger 20 is a spider 21 which is operatively connected to the toggle 18 by a link 22. Pivotally mounted on the free end portions of oppositely extending legs of the spider 21 are foot pedals 23 which are operable in openings 24 provided therefor in the plate 19. The shanks of the pedals 23 are notched, as at 25, for engagement with the plate 19 for releasably locking said pedals in depressed position. It will thus be seen that the impression roller 14 may be conveniently swung upwardly away from the cylinder 2 when desired by simply rocking the spider 21 in a direction to elevate the rod 15 through the toggle 18. It will further be seen that the supporting means for the impression roller 14 may be conveniently adjusted vertically as desired for various sizes of cylinders by rotating the shaft 10. If desirable or necessary, any suitable means may be provided for retaining the rack bars 6 in vertically adjusted position.

The reference numeral 26 designates an inclined, vertically adjustable feed board having a guide 27 thereon. Extending transversely across the lower portion of the feed board 26 is a series of openings 28, the purpose of which will be presently set forth. The feed board 26 is adjustably supported by pairs of links 29 which are pivotally connected to nuts 30 which are mounted on the oppositely threaded end portions of screw shafts 31 which are coupled to each other for operation in unison by a chain and sprocket connection 32.

100

105

110

A hand wheel 33 is provided for raising or lowering the feed board 26.

Journalled in the free end portions of the arms 13 are brackets 34 (see Figure 5) in which a feeder frame 35 is secured by set screws 36. It will thus be seen that the feeder frame 35 is mounted for swinging movement in a vertical plane on the arms 13. Stop lugs 37 which project from the arms 13 limit the downward swinging movement 10 of the frame 35.

Fixed on the free end of the frame 35 are bearing blocks 38 and 39 in which a shaft 40 is journalled, said shaft 40 projecting laterally beyond the block 38 and having fixed on its projecting 15 end portion a pulley 41. Fixed at spaced points on the shaft 40 are feeding disks or wheels 42.

The bearing block 38 has slidably mounted thereon an elongated housing 43 having longitudinal slots 44 therein which accommodate the shaft 20 40. Journalled longitudinally in the housing 43 is an adjusting screw 45 which is threaded through the bearing block 38 and which has fixed on one end a hand wheel 46. Journalled transversely on the lower end portion of the housing 43 is a shaft 25 47 having pulleys 48 and 49 fixed on its end portions. An endless belt 50 is trained around the pulley 49 and around a pulley 51 on the upper portion of the housing 43, the flights of said belt 50 being engaged with diametrically opposite sides 30 of the pulley 41 for actuating the shaft 40. The pulley 48 rides on a cam 52 which is fixed on the cylinder shaft 53, said cam 52 constituting means for driving the feeder and for periodically raising and lowering the same.

Extending between the bearing blocks 38 and 39 is a bar 54 having mounted thereon a plurality of stops 55 which are operable in the openings 28 in the feed board 26. The construction of the feeder is such that when the disks or wheels 42 are raised 40 to inoperative position by the cam 52 the stops 55 are projected above the upper surface of the feed board 26 for engagement by the next sheet that is to go into the press. Of course, when the feed disks or wheels 42 are lowered into engagement 45 with the sheet the stops 55 are retracted or lowered to permit the passage of said sheet. This is illustrated to advantage in Figure 7 of the drawings.

When the low portion of the cam 52 reaches the 50 pulley 48 the feeding mechanism swings downwardly by gravity for engaging the disks or wheels 42 with the sheet, as will be apparent, and when said low portion of the cam passes the pulley 48 the feeding mechanism is raised to inoperative 55 position. However, it will be noted that the feeder disks or wheels 42 are in constant operation. When the impression roller 14 is swung upwardly or raised the lugs 37 support and raise the feeding mechanism. When a web or roll, instead 60 of sheets, is to be fed into the press, the feeding mechanism is simply swung upwardly and forwardly to an out of the way position on the arms 13.

It is believed that the many advantages of a 65 printing press constructed in accordance with the present invention will be readily understood, and although a preferred embodiment of the invention is as illustrated and described, it is to be understood that changes in the details of construction 70 and in the combination and arrangement of parts may be resorted to which will fall within the scope of the invention as claimed.

What is claimed is:—

1. In a printing press comprising a supporting 75 structure and a cylinder operatively mounted on

said supporting structure, an impression roller cooperable with the cylinder, means for swingingly mounting the impression roller on the supporting structure, and a sheet feeding mechanism swingingly mounted on the impression roller mounting means. 80

2. In a printing press comprising a supporting structure and a cylinder operatively mounted on said supporting structure, an impression roller cooperable with the cylinder, means for mounting the impression roller on the supporting structure for swinging movement toward and away from the cylinder, means connected with the impression roller mounting means for manually swinging said impression roller toward and away from the cylinder, and a sheet feeding mechanism swingingly mounted on the impression roller mounting means. 85

3. In a printing press comprising a supporting structure and a cylinder operatively mounted on said supporting structure, an impression roller cooperable with the cylinder, means for mounting the impression roller on the supporting structure for sliding and swinging movement toward and away from the cylinder, means for manually 100 sliding the impression roller toward and away from the cylinder, means for manually swinging the impression roller toward and away from the cylinder, and a sheet feeding mechanism swingingly mounted on the impression roller mounting 105 means.

4. In a printing press comprising a supporting structure and a cylinder operatively mounted on said supporting structure, a cam rotatable in unison with the cylinder, and a sheet feeding 110 mechanism pivotally mounted on the supporting structure, said mechanism including a rotary shaft, feed wheels fixed on the shaft, and means operatively connecting the shaft to the cam for actuation thereby and for raising and lowering 115 the sheet feeding mechanism.

5. A printing press comprising a supporting structure and a cylinder operatively mounted on said supporting structure, a cam rotatable in unison with the cylinder, a frame pivotally 120 mounted on the supporting structure, bearings mounted on the frame, a shaft journalled in the bearings, feed wheels mounted on the shaft, a member slidably mounted on one of the bearings, means for adjusting the member on said 125 one bearing, and means on the member engaged with the cam for operatively connecting the shaft to said cam for actuation thereby, and for raising and lowering the feed wheels.

6. A printing press comprising a supporting 130 structure and a cylinder operatively mounted on said supporting structure, a cam rotatable in unison with the cylinder, a frame pivotally mounted on the supporting structure, bearings mounted on the frame, a shaft journalled in the 135 bearings, feed wheels mounted on the shaft, a member slidably mounted on one of the bearings, means for adjusting the member on said one bearing, and means on the member engaged with the cam for operatively connecting the shaft to 140 said cam for actuation thereby and for raising and lowering the feed wheels, the last-named means comprising a pulley fixed on the shaft, another shaft rotatably mounted on the member, pulleys fixed on the second named shaft, one of the second named pulleys being engaged with the cam, and an endless belt connecting the first-named pulley to the other of the second-named pulleys. 145

7. In a printing press comprising a supporting structure and a cylinder operatively mounted on 150

said supporting structure, a cam rotatable in unison with the cylinder, a feed board mounted for vertical adjustment on the supporting structure, said feed board having openings therein, a frame pivotally mounted on the supporting structure, feed wheels mounted on the frame, means operatively connecting the feed wheels to the cam for rotation thereby and for raising and lowering said feed wheels, and stop means mounted on the frame and operable in the openings in the feed board.

5 80

10 85

8. In a printing press comprising a supporting

structure and a cylinder operatively mounted on said supporting structure, an impression roller cooperable with the cylinder, means for mounting the impression roller on the supporting structure for sliding and swinging movement toward and away from the cylinder, means for manually sliding the impression roller toward and away from the cylinder, and means for manually swinging the impression roller toward and away from the cylinder.
